UNITED STATES PATENT OFFICE.

STEWART D. RODGERS, OF PITTSBURGH, PENNSYLVANIA, ASSIGNOR OF ONE-FOURTH
TO CLARENCE G. HILDRETH, OF PITTSBURGH, PENNSYLVANIA.

AUTOMATIC TRAIN-CONTROL SYSTEM.

1,359,839.

Specification of Letters Patent. Patented Nov. 23, 1920.

Application filed November 9, 1916. Serial No. 130,446.

To all whom it may concern:

Be it known that I, STEWART D. RODGERS, a citizen of the United States, and a resident of Pittsburgh, in the county of Allegheny and State of Pennsylvania, have invented a new and useful Improvement in Automatic Train-Control Systems, of which the following is a specification.

This invention relates to automatic train control systems. It is particularly applicable to steam railways in connection with the block signal systems thereof, but it may be also applied to other railways, such, for example, as electric railways.

The invention is adapted to be used with any suitable block system of railway signaling and is designed to automatically prevent a train running past signals which have been set against it. The system is arranged so that in case a train comes into a block immediately behind another train, a caution signal is first flashed in the engineer's cab and later a danger signal is flashed and the brakes automatically applied to reduce the speed of the train to a safe controllable limit. In case the train is not entirely stopped it is automatically stopped by a further application of the brakes when the train reaches what is known as the stop signal station.

The invention is an improvement upon the system disclosed in my co-pending application, filed April 24, 1915, Serial No. 23,710.

One of the objects of the invention is to provide an improved automatic train control system which will operate signals within the cab of the engine in case of danger on the block ahead.

A further object is to provide an improved automatic train control system in which the train will be automatically stopped in case of danger on the block ahead even though the engineer does not see or disregards the signals.

A further object is to provide an improved train control system in which the speed of the train is reduced in case of danger ahead by setting the brakes and in which the brakes are automatically released as soon as the train gets down to a predetermined slow speed.

A further object is to provide an improved automatic train control system in which, when the train gets down to a predetermined slow speed, if it is not stopped before reaching a certain point, it will be au-

tomatically stopped by further application of the brakes.

A further object is to accomplish all the above functions by means of an improved system in which it is unnecessary to have sections of the railway track insulated.

Other objects and advantages of the invention will hereinafter appear.

The accompanying drawings illustrate an embodiment of the invention. The views of the drawings are as follows:

Fig. 1 is a diagrammatic view of the railway track and the track circuits therefor.

Fig. 2 is a side elevation of the semaphores of a block signal system, showing the manner in which the semaphores control the circuits of the automatic train control system.

Fig. 3 is a diagrammatic view of the wiring and of the apparatus on the engine.

Fig. 4 is a side elevation and partial cross section of the contact shoe carried on the train.

Fig. 5 is a side elevation of the contact shoe, the batteries and the switchboard for controlling the circuits.

Fig. 6 is a cross section of one of the electromagnets located along the track, said view showing the position of the shoe carried on the train with relation to the magnet.

Fig. 7 is a top plan view of a portion of one of the magnets located along the track.

The track circuits will first be described, after which the operative apparatus on the engine will be explained. It may be stated, however, that the signals and other apparatus on the engine are rendered operative by means of a shoe carried on the train which is attracted by magnets located along the track. When the track is clear the magnets therealong are not energized and therefore do not attract the shoes on the train and consequently the apparatus on the engine is not operated as long as the track is clear. However, when there is a train in the preceding block, the magnets in the block behind are energized, and if a train runs into this block the magnets attract the shoes on the engine and operate the apparatus carried thereby.

Referring to Fig. 1, the section of railway track between the point A and the point B constitutes one block of an ordinary block signal system, the direction in which the trains run thereover being indicated by

the arrow. The invention can be used in connection with any system of block signaling, and Fig. 1 illustrates only the semaphores of such a system without showing the 5 circuits for operating them.

A block signaling system usually has one or more semaphores, two being shown in this instance, which are normally in upright position, as illustrated at the left-hand end 10 of Fig. 1. These semaphores are controlled by trains in the block ahead of the one illustrated in the drawings, that is, the block immediately to the left of the point B in Fig. 1. When there is no train on the block at

- 15 the left of point B, both the semaphores are in the position shown. When there is a train in the block at the end thereof adjacent the point B, both the semaphores are down in a horizontal position, the combined position of the semaphores meaning "danger,"—that is, when there is a train very close in the block ahead. When the train has moved to the left-hand end of the block, one of the signals, the upper one 20 in this case, moves up, but the other remains in horizontal position, the combined positions of the two semaphores being at such a time in what is known as "caution position," that is, they caution the engineer that 25 there is a train in the next block, though it may be some distance away.

As hereinbefore stated, the semaphores shown in Fig. 1 are controlled by the block at the left of the point B. These semaphores are positioned, however, so as to be 30 observable from the block illustrated in Fig. 1.

It is, of course, to be understood that in some cases only one semaphore is used which 40 has three positions, or more than one semaphore may be used with each semaphore located separately. The exact location and the number of the semaphores is not important in the present invention, since for an 45 operation of the system herein described it is merely necessary to have electrical contacts associated with the semaphore or semaphores to control the circuits of the automatic train control system.

50 Near the right-hand end of the block shown in Fig. 1, is located an electromagnet 1 in a position relative to the block which is called "caution position." At about the center of the block and on the opposite side 55 of the track is located an electromagnet 2 in what is called "danger position." At the left-hand end of the block and on both sides of the track are located electromagnets 3 and 4 in what is called "stop position."

60 When the track is clear, all of these electromagnets are deenergized and have no effect upon the apparatus located on the passing train. When, however, there is a 65 train at the right-hand end of the block immediately preceding to the left, all of the

electromagnets will be energized and the apparatus on a train coming into the block will be successively operated, first, by the caution magnet to give a caution signal, second, by the danger magnet to give a danger 70 signal and apply the brakes, and finally by the stop magnets to further apply the brakes to stop the train. In case the train in the preceding block is almost off the block, only the caution magnet 1 will be energized and consequently the apparatus on a train coming into the block illustrated in Fig. 1 will be operated only as it passes the caution magnet to give a caution signal to indicate to the engineer that he should run 75 carefully.

The circuits by means of which the electromagnets are supplied with energy will first be explained and then the manner in which the circuits are controlled by the 80 semaphores will be described.

Each of the electromagnets is energized, preferably by a direct current of relatively low voltage, as for example, 6 to 10 volts. They may, however, be energized by current 90 of higher voltage or by alternating current, if desired. There may be a separate source of energy for each electromagnet, or a number of electromagnets may be energized from a common source. In the present sys- 95 tem energy is supplied to each of the electromagnets by storage batteries 5 which are located in the vicinity of the electromagnets. These storage batteries are supplied with energy from the direct current line 6 common to a plurality of the batteries and their electromagnets located along the railway track. Energy is preferably supplied to the direct current line from an alternating current line 7 through a transformer 8 and 100 rotary converter 9.

Each of the batteries has an amperehour-meter 10 associated therewith which, when the battery charge decreases below a predetermined amount, connects the battery to 110 the direct current source of supply to charge the same.

The circuits of each of the electromagnets and their associated storage batteries and charging systems are substantially alike 115 and therefore only one will be described in detail. The circuit of electromagnet 1 is as follows:

Current from the storage battery 5 passes through the shunt 11 of the amperehour-meter, the conductor 12, contact 13, and armature 14 of relay 15 when said relay is deenergized and the armature is in engagement with the contact 13, said armature being biased into engagement with said 120 contact, when the relay is deenergized, by means of a spring 16. From the armature 14 current passes through conductor 17 to the electromagnet 1 and returns from the same through the conductors 18 and 19 to 130

the opposite side of the storage battery. The electromagnet 1 is thus energized by the storage battery whenever the relay 15 is de-energized so that its armature is in engagement with the contact 13.

Whenever the energy of the storage battery decreases below a predetermined amount, a contact on the ampere hourmeter completes a circuit from the battery 5 through the conductor 20, the ampere hourmeter, the conductor 21, coil 22 of the switch 23 and conductor 24 to the opposite side of the battery. This closes the electromagnetic switch 23 and connects the direct current supply directly to the electromagnet 1, and also connects said supply so as to charge the battery 5. In order to prevent the battery being connected to the direct current source of supply when the voltage 10 of said supply is below the voltage of the battery, a switch 25 is provided, the coil 26 of which is normally across the direct current supply wires 27 and 28. When the voltage of the direct current supply is equal 15 to or above the required minimum limit for charging the batteries the coil 26 pulls the switch 25 closed. The switch 25 is normally biased to open position so that in case the voltage drops below the desired charging value, the switch is automatically 20 opened.

Assuming that both the switches 23 and 25 are closed, the current to the electromagnet 1 from the direct current supply 25 line 6 is through conductor 28, switches 25 and 23, conductors 24 and 12, the armature 30 of relay 15, when said armature is in engagement with the contact 13, conductor 17, electromagnet 1, and conductors 18 and 27 35 to the other side of the direct current supply line. At the same time the batteries are being charged from the supply line in a manner well understood.

The electromagnet 2 is connected to the direct current supply line 6 in a similar 45 manner, its circuit being controlled by the relay 29. It is also provided with a storage battery 5 charged from the direct current supply line 6 through the usual battery 50 charging system including an amperehourmeter 10.

The "stop" electromagnets 3 and 4 are connected in parallel to the direct current supply circuit 6 in the same manner as the other electromagnets. They are controlled 55 by a relay 30 and have a storage battery 5 connected so as to supply energy to them and to be charged by the direct current line 6 through a battery charging system including an ampere hourmeter 10.

The circuits of the electromagnets 1, 2, 3 and 4 are controlled as follows:

The caution semaphore 31 and the danger semaphore 32 are each provided in this instance with an extension for controlling the

circuits of certain of the electromagnets. It is not absolutely necessary to have extensions directly on the semaphores for controlling the circuits, but some suitable arrangement should be provided so that when 70 the semaphores move they control the circuits of the electromagnets. A relay in shunt to the relay of the ordinary block signal circuit may be used for controlling the electromagnet circuits. 75

The lower or caution semaphore 31 has an extension 33 which controls contacts 34 and 35. Contact 34 is connected by means of conductor 36 to a source of energy 37, and contact 35 is connected by means of conductor 38 to the relay 15 controlling the circuit of the "caution" electromagnet 1.

The upper or danger semaphore 32 has an extension 39 which controls contacts 40 and 41. The contact 41 is connected to the 85 source of energy 37, and the contact 40 is connected by means of conductor 42 to the relay 30 controlling the "stop" electromagnets 3 and 4. Contact 40 is also connected through conductor 42 and conductor 43 to 90 the relay 29 controlling the circuit of the danger electromagnet 2.

The opposite end of the winding of the "caution" relay 15 and the opposite ends of the windings of the "danger" and "stop" 95 relays 29 and 30 are connected to one of the rails of the track, to which rail is also connected the side of the source of the energy 37 opposite that to which the conductor 36 is connected. 100

It will thus be seen that the lower or "caution" semaphore 31 controls the circuit of the relay 15 which in turn controls the circuit of the "caution" electromagnet. The danger semaphore 32 controls the circuits 105 of the "danger" relay 29 and the "stop" relay 30 which in turn respectively control the "danger" electromagnet 2 and the "stop" electromagnets 3 and 4.

Accordingly, when the track is clear and 110 both of the semaphores are in their upright positions as illustrated, the circuits of all the relays are closed by the contacts on the semaphores, and consequently the armatures of all the relays are attracted and the circuits of all the electromagnets are open so that these electromagnets are deenergized and the apparatus on a passing train is not affected. 115

If a train should be at the far end of the 120 block to the left of the point B so that the caution semaphore 31 is down, the circuit including the contacts 34 and 35 will be open, and consequently the relay 15 will be deenergized, as a result of which its armature 125 14 will be pulled over by a spring 16 into engagement with contact 13, thereby completing the circuit of "caution" electromagnet 1 and energizing the same. Accordingly, if a train comes into the block illus- 130

trated in the drawing past the electromagnet 1, the apparatus on the engine will be operated to give a "caution" signal.

In case there is a train in the near end 5 of the block to the left of the point B so that both the semaphores 31 and 32 are down, the circuits of all the relays 15, 29 and 30 will be open, and consequently their armatures will be pulled over by the springs associated 10 therewith into engagement with the respective contacts, and all the electromagnets 1, 2, 3 and 4 will be energized, so that any train coming into the block illustrated in the drawing, will, as it passes the successive 15 electromagnets, have the apparatus on its engine operated so as to first give a "caution" signal, then a "danger" signal and an application of the brakes, and then a later application of the brakes to stop the train.

20 The apparatus carried by the engine is illustrated in Fig. 3 and is as follows:—

The engine or tender or some car of the train carries two movable shoes 45 and 46, one on each side of the tender or car. The 25 shoes are made of magnetic material and are arranged to be moved magnetically when they come into the vicinity of an energized electromagnet along the track. Each of the shoes is grounded to the frame of the tender 30 or car upon which it is mounted so that there is normally an electric circuit from one shoe through the truck frame to the other. The shoe 45 is connected to a switch 47 normally biased into an engagement with a contact 35 48 by a spring 49. The shoe 46 is connected to a switch 50 normally biased into engagement with the contact 51 by a spring 52. Located upon the engine, and preferably in the cab, is the green or caution signal 53 40 and the red or danger signal 54. Also, located at suitable points on the train is the electromagnetic valve 55 for controlling the air brakes.

45 Energy is supplied for operating these various devices on the train by means of a battery 56, which is connected through the conductor 57, the relay winding 58, armature 59 to the conductor 60, from which it goes in one direction through the relay winding 61, to conductor 62 and the shoe 45 to the truck frame, and in the other direction through the relay 63, the conductor 64 and the shoe 46 to the truck frame. The opposite side of the battery is connected by conductor 65 through the reversing switch 66, the conductor 67, the pilot light 68 and the magnet winding 69 of the brake controlling valve to the truck frame and thence through shoes 45 and 46 to the opposite side of the 55 battery. It will accordingly be clear that with the apparatus in the position shown, all of the relays 58, 61 and 63 will be in the position shown and the electromagnet 69 of the brake valve will be energized to hold 60 its plunger 70 in the position illustrated.

With the devices in the position shown there is also a circuit from the negative side of the battery, through the conductor 71, the armature 72 of relay 61, the conductor 73, the resistance 74, the conductor 75, the 70 switch blade 76 of the reversing switch, the conductor 77, the relay winding 78, a bridging contact 79 operated by the relay winding and the pilot light 80, the conductor 67, the middle blade of the reversing switch, 75 and the conductor 65 to the positive side of the battery.

There is also a circuit from the negative side of the battery through the conductor 81, the armature 82 of the relay 63, the resistance 83, the conductor 84, switch blade 85 of the reversing switch 66, conductor 86, relay winding 87, a bridging contact 88, operated by the relay winding, the conductor 89, relay winding 90, conductor 91, pilot 85 lamp 92, and conductor 67 through the reversing switch to the positive side of the battery.

When, however, the train passes an energized "caution" electromagnet along the 90 track, the shoe 45 is drawn down and the circuit of the relay 61 is opened by the switch 47. The relay 61 is thus momentarily deenergized, allowing its armature 72 to be drawn back by the spring, and opening the 95 circuit from the negative side of the battery through the armature 72, conductors 73 and 75, and reversing switch to the relay 78. The relay 78 is thus deenergized and its bridging member 79 drawn down by the 100 spring associated therewith into engagement with the contacts 93 and 94. This completes a circuit from the negative side of the battery, through the conductor 71, resistance 95, conductor 96, bridging member 79 of relay 105 78, conductor 97, the caution signal 53 to the conductor 67, and through the reversing switch to the positive side of the battery. A bell 98, or other audible signal, is connected in parallel with the visible caution 110 signal in order to attract the attention of the engineer in case he is not looking at the signal. The circuit to the electromagnet 69 of the brake controlling means is still maintained and said means is not disturbed.

115 If the train now passes an energized danger electromagnet, the shoe 46 is drawn down, opening the circuit of relay 63 and allowing its armature 82 to be momentarily withdrawn by the spring associated with it. 120 This opens the circuit from the negative side of the battery through the relay armature 82 to the relays 87 and 90. When the relay 87 is deenergized, the bridging member 88 is drawn down by the spring associated 125 therewith into engagement with the contacts 99 and 100. This completes a circuit from the negative side of the battery through the conductor 81, the resistance 101, conductor 102, the bridging member 88 of 130

relay 87, the red or danger signal 54, the conductor 67 and the reversing switch to the positive side of the battery. A bell, or other audible signal 103 is connected with the visible danger signal 54 to draw the engineer's attention to the danger signal in case he is not looking at the same.

Relay 90 is deenergized simultaneously with the relay 87, whereupon its armature 104 is withdrawn by the spring 105, allowing the armature 106 to be drawn down by the spring 107 into engagement with the contact 108. This completes a circuit from the wire 67, through a conductor 109, armature 106, conductor 110, contact lever 111, contact 112 and conductor 113 to ground. This circuit is devoid of any electromagnet coils of high resistance, such as the winding 69 of the brake controlling means, hence the current flows to ground through this circuit instead of through the electromagnet 69. The electromagnet 69 is accordingly practically short circuited, or at least deenergized sufficiently to allow the plunger 70 to drop by gravity or be forced downward by a train pipe pressure or spring if such is employed. The downward movement of the plunger vents the train pipe pressure of the air brake system and applies the brakes in the manner well understood in the air brake art.

It will thus be clear that when the train passes an energized danger electromagnet the danger signal 54 is flashed and the electromagnet 69 is deenergized to allow the train pipe pressure to be vented to apply the brakes.

The brake controlling means comprises an electromagnet 69 controlling a plunger 70, having a valve 114 on the end thereof for controlling communication between the chambers 115 and 116. The train pipe 117 of the air brake system is connected to the chamber 115. The chamber 116 has an opening therein at one side to which is connected a vent valve 118. This vent valve has a plurality of small holes therein for permitting pressure to escape from the chamber 116 gradually, the rate at which the pressure escapes being controllable by an adjustable screw 119. When the electromagnet 69 is deenergized the plunger 70 moves downwardly and opens communication between the chambers 115 and 116. This allows the train pipe pressure to escape from the pipe 117 through chambers 115 and 116 and the vent valve 118. The pressure escapes very slowly, however, and the brakes are only gradually applied, as will be well understood. Inasmuch as the brake controlling means is operated when the train passes a danger signal the gradual application of the brakes slows down the speed of the train sufficiently to prevent its running rapidly past the "stop" electromagnets.

The speed responsive mechanism shown in the upper left hand corner of Fig. 2 is mounted on the engine or tender and comprises an ordinary centrifugally operated governor suitably geared to the engine or tender. This governor controls the lever 111 which engages the contacts 112 and 120. When the speed of the train is reduced by an application of the brakes after the train runs past a danger signal, the speed governor moves the lever 111 upwardly and out of contact with the contact 112. The governor may be adjusted so that at a certain predetermined speed, for example, six miles an hour, the lever 111 stands between the contacts 112 and 120. The circuit to ground is thus broken through conductor 113 and the current flows to ground through the electromagnet 69 which is again energized. The plunger 70 is thus drawn up, shutting off communication between the chambers 115 and 116 and preventing any further venting of the train pipe pressure.

Accordingly, when the train runs past the danger signal the brakes are applied until the speed reaches a predetermined amount, say six miles per hour, whereupon the brakes are again released, permitting the brakes to be released in case the block ahead is clear.

If, however, the track ahead is still occupied by a train and the engineer does not stop when the speed of his train is reduced to six miles an hour, but continues to run up to the point where the stop magnets are located, the following action takes place:

As the train passes the stop magnets both of the shoes 45 and 46 are drawn down and the circuit to ground through both of the shoes is broken by opening of the switches 47 and 50. This deenergizes both relays 61 and 63 and also relay 58, whose armature 59 is drawn down by the spring associated therewith. This disconnects the negative side of battery 56 from both shoes 45 and 46 so that there is no return circuit from ground to the negative side of the battery. Consequently the electromagnet winding 69 of the brake valve will be deenergized and the train pipe 117 entirely vented to fully apply the brakes and stop the train.

The operation of the system as a whole is briefly as follows:

When the track is clear both of the semaphores 31 and 32 are in upright position and the circuits of all the relays 15, 29 and 30 are energized so that the circuits of the electromagnets 1, 2, 3 and 4 are open and said electromagnets are deenergized. The devices on any train passing through the block will accordingly not be operated and no signals will be given.

If there is a train in the block at the left of the point 3 but at the far end thereof, so that only the semaphore 31 is down, the

circuit of relay 15 will be opened and the circuit of the electromagnet 1 closed, so that said electromagnet is energized. When a train enters the block illustrated under 5 these conditions, the shoe 45 is drawn down by the electromagnet, thereby deenergizing the relays 61 and 78 on the train and energizing the caution signal 53 to inform the engineer that there is a train in the block 10 ahead.

If the train in the block ahead is near enough to cause both of the semaphores to be down, the circuits of all the relays 15, 29 and 30 will be open and the circuits of all 15 of the electromagnets 1, 2, 3 and 4 will be closed, so that said electromagnets will be energized and the shoes 45 and 46 on the train will be drawn down successively as the train passes the electromagnets. The 20 shoe 45 will first be operated and the caution signal given. As the train then runs past the electromagnet 2, the shoe 46 will be operated to deenergize the relays 63, 87 and 90 on the train to flash the danger signal 25 and gradually apply the brakes. When the speed of the train has been reduced to a predetermined amount the speed responsive device will cause the brakes to be released and allow the train to proceed if the train ahead 30 in the next block has left said block. If, however, the train in the preceding block has not left the block, so that the electromagnets 3 and 4 are energized, then when 35 the train proceeds past the stop electromagnets both of the shoes 45 and 46 will be simultaneously drawn down to thereby deenergize all the relays on the train and further apply the brakes to positively stop the train.

40 In order to re-set the apparatus on the train after the train has run past the caution, danger and stop signals, it is necessary for the engineer to close the manual switch 121, thereby completing a circuit 45 from the battery 56 through the relay 58 and relay 61 and shoe 45 to ground and relay 63 and shoe 46 to ground. This energizes relays 58, 61 and 63 causing them to pick up their armatures.

50 The engineer also manually moves upwardly the bridging member 79 of relay 78, the bridging member 88 of relay 87, and the pivoted member 106 associated with relay 90. In order that this may be easily done, 55 the relays 78, 87, 90 and the switch 121 are located at a convenient point in the engine cab.

The switch 121 need be closed only for an instant because, as soon as it is closed, the 60 relay 58 is energized and the armature 59 attracted to complete the circuit to the shoes 45 and 46 and maintain said circuit closed. The switch 121 is normally biased to open position so that as soon as pressure thereon 65 is relieved it automatically opens.

The bridging members of relays 78 and 87 also need be held closed only an instant because as soon as they are moved upwardly the circuits of the respective relay windings are closed, thereby energizing the relays and 70 causing them to hold the bridging members in position.

The movable member 106 also need be held in its upward position only an instant because the relay 90 is energized and as soon 75 as the circuit of relay 87 is completed which causes relay 90 to attract its armature 104 and lock the member 106 in position.

In case the direction of travel of the train is reversed, the reverse switch 66 is thrown 80 from the position shown in Fig. 3 to the reverse position. In the latter position the relay 78 and the caution signal are connected to be controlled by the relay 63 and the shoe 46, and the relays 87 and 90 and the danger 85 signals are connected to be controlled by the relay 61 and the shoe 45.

A preferred construction of the shoe carried by the train is illustrated in Fig. 4. It comprises a body 125 supported at its sides 90 on rods 126 and 127 attached to the locomotive or tender. Springs 128 are placed between the ends of the rod and the body and between stops 129 on the rod in the body 95 so that the shoe is spring-suspended and normally biased to assume an intermediate position, in which position the contact 130 carried by one arm of the bell crank lever 131 is in engagement with the contact 48 connected to the conductor 62. 100

The shoe may be supported from the bottom of a platform 132 illustrated in Fig. 5, which platform forms the bottom of a receptacle containing the battery for operating the relays and a switchboard 133 upon 105 which the relays are mounted. Any other suitable construction of shoe may be employed.

The construction of the electromagnets located along the track is shown in Fig. 6. 110 These electromagnets have considerable length and are of a type known as the "horn" type, that is, one of the poles of the electromagnet projects toward the rail and forms in effect a horn. The base of the electromagnet 134 may be attached to the rail by means of a clamp, as shown, or by any other suitable means. The electromagnet is provided throughout its length with a plurality of cores 135 around each of which is 120 located a magnet winding. A suitable cover 136 of non-magnetic material is provided and the space around the windings is preferably filled with oil. The horns 137 project toward the rail so that the rail forms a 125 part of the magnetic circuit of the magnet.

The position of the shoe 46 with reference to the magnet is shown in Fig. 5. The magnet energizes the rail sufficiently to cause the shoe to be drawn down into contact with it 130.

as the train passes. In some cases the shoe may be drawn into actual contact with the rail, but in any event the magnet is made strong enough to draw down the shoe at all speeds of the train sufficiently to cause the switch 47 to open its circuit.

A switch 138 is provided for maintaining the circuit closed as the reversing switch 66 is thrown from one position to the other. 10 This switch is normally biased to open position.

This system avoids the use of insulated rail sections which are generally expensive and difficult to maintain. There are no shoes 15 which continually slide on the rail. In fact, the operation of the system does not depend upon a sliding contact between a shoe on the train and a rail or a rail section along the track. Instead it merely depends upon 20 the drawing down or the movement of a shoe carried by the train by means of an electromagnet or other suitable means along the track. This shoe need not be drawn to actual engagement with the devices along 25 the track but need be only moved sufficiently to open the circuit on the train.

It is to be understood that the structure shown is for purposes of illustration only and that variations may be made therein 30 and other structures devised which come within the spirit and scope of the appended claims.

I claim—

1. A train control system comprising automatic track signal mechanism having caution and danger positions, a caution electromagnet located on one side of the railway track, a danger electromagnet located 35 on the opposite side of the track, and stop electromagnets located on both sides of the track, said electromagnets being arranged so that the caution magnet is energized when the track signal mechanism is in caution position and the danger and stop electromagnets are energized when the track 40 signal mechanism is in danger position, brake controlling means carried by the train, a caution and a danger signal on the train, electrical circuits on the train for said signals and brake controlling means, means on one side of the train responsive to the energized caution electromagnet for controlling the electric circuits to operate the caution signal on the train, means on 45 the opposite side of the train responsive to the energized danger electromagnet for controlling the electric circuits to operate the danger signal and apply the brakes, speed responsive mechanism carried by the train 50 for releasing the brakes when the train speed decreases to a predetermined limit, the mechanisms carried by the train for controlling the electrical circuits being arranged so that both are operated by the
2. A train control apparatus comprising a brake operated means on the train, a normally closed circuit including a magnet for preventing the operation of the brake controlling means, two mechanisms connected in parallel in said closed circuit and arranged to be responsive to devices along the track for interrupting the normally closed 55 circuit, two signal devices on the train, a normally open circuit through each of said signals, means for closing one of said open circuits on the operation of one of said mechanisms, and means for closing the other open circuit upon operation of the other controlling mechanism.
3. Train control apparatus comprising an electromagnetic brake controlling valve, a circuit for controlling said valve normally maintained closed by two movable mechanisms carried by the train and connected in parallel to the closed circuit, said mechanisms being responsive to devices along the track, a caution and a danger signal on the train, normally open electric circuits for said signals, means for closing the circuit of the caution signal when one of the mechanisms is energized to open its branch of the normally closed circuit, and means for closing the circuit of the danger signal when the second mechanism is subsequently operated to open its branch of the normally closed circuit, the simultaneous operation of both mechanisms opening both branches 100 of the circuit of the electromagnetic brake valve so that the brake valve is operated to apply the brakes to the train.
4. Train control apparatus comprising a brake control valve normally biased to vent the train pipe pressure to apply the air brakes, an electromagnet for holding said valve closed, a closed electric circuit on the train normally energizing said magnet, said circuit having branches, movable means carried by the train arranged to be moved by devices along the track for interrupting one branch of said normally closed circuit, a second movable means arranged to be operated by devices along the track for interrupting a second branch of said normally closed circuit, a caution signal on the train, a normally open circuit through said caution signal, a danger signal on the train, a normally open circuit through said danger signal, and means for closing the circuit of the caution signal when the first movable means is operated to interrupt its branch of the normally closed circuit, and means for closing the circuit of the danger signal 115 when the second movable means is operated to interrupt the second branch of the normally closed circuit, the interruption of

- both branches of the normally closed circuit serving to completely interrupt said circuit and allow the brake valve to open to cause the brakes to be applied.
5. A train control apparatus comprising a brake valve normally biased to vent the train pipe pressure to apply the brakes, an electromagnet for holding said valve closed, a normally closed circuit for said electromagnet having two branches, each of said branches having means therein by which it may be interrupted; movable magnetic shoes connected to said interrupting means and responsive to energized electromagnets 10 along the track whereby as the train passes the electromagnets the shoes are operated to open the circuits, a caution signal on the train, a normally opened circuit for the caution signal, a danger signal on the train, 15 a normally open circuit through the danger signal, and means for closing the circuit through the caution signal when the first shoe is operated to interrupt its branch of the normally closed circuit, and means for closing the circuit of the danger signal when the second shoe is operated to interrupt the second branch of the normally closed circuit, the interruption of both branches completing the interruption of the normally closed circuit and thereby deenergizing the electromagnet to allow the brake control valve to vent the train pipe pressure and apply the brakes.
10. A train control apparatus comprising a brake valve normally biased to vent the train pipe pressure to apply the brakes, an electromagnet for holding said valve closed, a normally closed circuit for said electromagnet having two branches, each of said branches having means therein by which it may be interrupted; movable magnetic shoes connected to said interrupting means and responsive to energized electromagnets 15 along the track whereby as the train passes the electromagnets the shoes are operated to open the circuits, a caution signal on the train, a normally opened circuit for the caution signal, a danger signal on the train, 20 a normally open circuit through the danger signal, and means for closing the circuit through the caution signal when the first shoe is operated to interrupt its branch of the normally closed circuit, and means for closing the circuit of the danger signal when the second shoe is operated to interrupt the second branch of the normally closed circuit, the interruption of both branches completing the interruption of the normally closed circuit and thereby deenergizing the electromagnet to allow the brake control valve to vent the train pipe pressure and apply the brakes.

In testimony whereof I have hereunto set my hand.
